UNITED STATES PATENT OFFICE.

WALTER THOMAS, OF NANAIMO, BRITISH COLUMBIA, CANADA.

REVOLVING RETORT.

1,201,531.

Specification of Letters Patent. Patented Oct. 17, 1916.

Application filed June 4, 1915. Serial No. 32,166.

To all whom it may concern:

Be it known that I, WALTER THOMAS, a subject of the King of Great Britain, residing at Nanaimo, British Columbia, Canada, have invented certain new and useful Improvements in Revolving Retorts, of which the following is a specification.

This invention relates to a revolving gas-fired retort for distilling coal, generating illuminating gas, producing coke and other valuable products.

The principal object of my invention is to provide for more rapidly and uniformly carbonizing coal at a lower temperature than is possible with the methods and apparatus now generally in use in the manufacture of gas, whereby destructive decomposition of the valuable volatile illuminants will be avoided—resulting in an increased yield of gas—and whereby inferior grades of coal, or practically waste coal of the dumps, can be economically and profitably distilled for production of gas, benzol, motor spirits and other valuable products.

Another object of my invention is to provide a revolving retort which can be uniformly heated while in motion by numerous gas flames—discharging at different points into passages throughout its length and circumference,—including means for feeding fuel gas to a plurality of Bunsen burners, in the length of a passage or flue, means for conducting off illuminating gas as generated, means for continuously or periodically feeding coal to the revolving retort, and means for discharging the resulting coke as required; and certain details of construction, as will appear in the following description and embodied in the claims.

The matter constituting my invention will be defined in the claims.

I will now describe the details of construction by reference to the accompanying drawings, in which:

Figure 1 represents a longitudinal vertical section of a revolving retort and its connections for feeding coal and discharging coke, and operating gearing in elevation. Fig. 2 represents a transverse section on line 2—2, Fig. 1, looking to the right. Fig. 3 represents a transverse section in line 3—3, Fig. 1, looking toward the left hand end of the retort. Fig. 4 represents a sectional diagrammatic view of a stationary re-

tort, illustrating the slow distillation of coal in a quiet state. Fig. 1^a represents details of gearing of modified construction.

Heretofore, in the manufacture of illuminating gas, the coal has been subjected to distillation in an inert body or quiet state, in stationary retorts—either of the horizontal, inclined or vertical variety—requiring the application of very high heats,—2,000° to 2,500° F. during an excessively long period of time, ranging from four hours to twenty four hours. The coal lying in an inert mass, Fig. 4, will be heated through from the surface to the center very slowly, and after the volatile matter is evolved from, or near, the outer surface a comparatively long time is required for the heat to penetrate the mass to the center, and in order to hasten the operation excessively high heats or temperatures are applied, with the result that much of the valuable volatile hydrocarbon illuminants are destructively decomposed, causing carbon to be deposited as lamp black, while only low grade marsh gas is passed off to the hydraulic main. In the present method also the body of coal is heated quite unequally at different stages, being at first comparatively cool, and therefore giving off a large per cent. of unfixed vapors, and toward the end of carbonization being too highly heated and causing the valuable illuminating gases to be destructively decomposed, with the production of lamp black and poor gases. By my method of distilling or carbonizing coal in a revolving retort, heated by a plurality of gas flames discharging at different points into each of a series of flues, a uniform temperature is maintained and all the particles of carbon in the body are constantly being shifted and exposed to the heated surfaces of the retort, resulting in a more uniform quality and a higher candle power gas. The temperature can be accurately regulated and the whole operation can be conducted at a lower temperature and in a shorter time than by the methods now generally in use.

I also save much of the expense involved in the construction of fire clay benches and retorts and much of the expense for skilled labor. I am also enabled to utilize great quantities of low grade fuel at a profit, which is impossible with the present apparatus.

The revoluble retort A is constructed of a sheet or plate-iron shell a^4 and a fire-brick lining a , composed of special fire-brick having longitudinal ducts or passages a^5 , provided at one end of the retort with gas outlet ports a' . The shell and lining are provided with longitudinal lines of openings a'' for the Bunsen burners N arranged to discharge at numerous points into the passages or flues a^5 . At the discharge end of the retort there is riveted to the shell a turned iron annular casting a''' , which protects the fire brick lining and forms part of a stuffing-box b'' in which the end of the retort turns. The other part of the stuffing box is secured to the wall of the stationary discharge head or chamber F. At the inlet or feed end the retort is closed by a head B, having a central extended neck B^1 for feeding coal, said neck being connected to a stationary feeding duct B^2 by a stuffing-box b in which it turns. The head B is also provided with a series of radial gas inlet ducts b' which also extend along the neck B^1 to 10 an annular inlet groove c in the fixed collar C which is provided at each end with a stuffing box c' . A fuel-gas supply pipe C^1 connects with the collar at its groove c . With the ducts b' connect the longitudinal gas pipes C^2 which connect with the Bunsen burners N. The outer end of the coal duct B^2 is closed by a stuffing box b''' , through which is passed the shaft w of screw-conveyer W. A stand E, supports the coal duct 20 B^2 and magazine Y and part of the operating gearing for the conveyer.

The discharge head or chamber F and coke chamber G are supported on an angular base piece H^1 over a conduit x for a coke car I. To the top of chamber F is secured a gas take-off pipe f which may connect with a hydraulic main or seal-box in a well known manner, but not here shown. The chamber has bolted to it a removable 30 cover-plate F^1 . To the lower end of the chamber is secured a valve casing f' , in which works a sliding gate valve f'' , having a screw-threaded stem f''' working through a threaded opening h in a supporting frame H. A coke chamber G is secured to the casing f' and has secured to its lower end a valve casing g containing gate valve g' provided with a screw-threaded stem g'' working through a threaded opening h'' . The 40 valve stems are provided with hand wheels j . The chamber G, with its upper and lower valves, provides an air and gas tight discharge for hot coke from chamber F and the retort.

The retort is supported by bearing wheels on rollers. Pillars K, having bearings k carry rollers k' which rest by their journals in the bearings, and the pillars are fixed on concrete foundations X. The bearing 50 wheels L are secured by their annular

flanges to the shell of the retort and rest on the rollers. Similar pillars K¹ carrying rollers k' and a wheel L¹ support the feeding neck B¹.

Bunsen burners N of a known kind and 70 having regulating valves n are secured to the shell a^4 at the openings a'' for discharging numerous flames into the ducts or flues a^5 . Numerous burners are used for maintaining a uniform and moderate temperature throughout the length and circumference of the retort, and so as not to cause cracking and breaking of the fire-brick lining by excessive heat at any one point. The gas will be supplied under pressure and take 75 in air at the Bunsen burners. The gas outlet ports a' open into stack Z, which, at its lower end encircles the retort and will be supported in a well known manner.

A worm wheel O is bolted by its flanges 80 to the shell a^4 and engages with a toothed wheel P, Fig. 1, p having on its shaft a beveled pinion p' meshing with a beveled pinion o' on the vertical shaft o , resting at its lower end in a bearing in a post o'' . A beveled gear wheel m on shaft o meshes with a beveled pinion r on the driving shaft R which rests in bearings on posts u and carries a belt wheel t'' . A clutch r' is connected in shaft R. A second shaft R¹, supported in bearings on posts u''' is provided for carrying a sprocket wheel q and has a clutch s for connecting it with, and disconnecting it from, the driving shaft. A motor T has on its shaft a small belt wheel t which connects by a belt t' with a large belt wheel U on a shaft u''' which carries a second and smaller belt wheel u'' . A belt S is passed over the wheels t'' and u'' for turning the 90 power shaft R.

The shaft w of conveyer W passes out through a stuffing box b'' and turns in a bearing v on frame E. To shaft w is secured a large sprocket wheel q' over which is passed a sprocket chain Q engaging also 100 with wheel q on shaft R¹. The coal magazine Y is secured to the fixed feeding duct section B² supported by frame E, and has at the top a hopper y and a slide valve y', the stem of which is connected to a hand lever y''.

The operating gearing is located as shown, simply for convenience of illustration, and in practice will be located in any convenient position with relation to the retort.

My revoluble retort will, in practice, be made about one hundred feet long in order to give the coal a sufficiently long exposure to the heat at a moderate temperature of about 900° F. Numerous Bunsen burners opening into the combustion passages or flues a^5 are, therefore, required in order to insure a uniform temperature throughout the length of the retort. This is also important in order to preserve the fire brick 120

from excessive heat at any one point, and to thus insure their greater durability.

The operation is very simple; the coal may be fed from the magazine continuously during the carbonizing operation, or at suitable intervals, according to the progress of distillation and evolution of gas in the retort. The Bunsen burners, after being lighted, will be regulated by the valves *n* to secure the desired temperature in the retort. The coke delivered into chamber *F* will, at intervals, be discharged into chamber *G* by opening valve *f''*, and after it has sufficiently cooled will be discharged into car *I* by opening valve *g'*, after having closed valve *f''*. The feeding of coal may be stopped by shifting the clutch *s* to disconnect the shaft *R'* from the power shaft *R*. The gearing which operates the retort may also be stopped by properly operating the clutch *r'*.

A worm *P'* engaging with the large worm wheel *O* on the retort, and beveled pinions *o'*, *p'* and vertical shaft *o* are shown in Fig. 1^a. This style of gearing may be used instead of the spur wheel *P* and its connections shown in Fig. 1.

Having described my invention, what I claim, and desire to secure by Letters Patent, is—

1. A revoluble retort having in its walls a series of longitudinal combustion passages provided at one end with outlet ports, a series of longitudinal gas supply pipes extending along the retort, a plurality of Bunsen burners connecting with said supply pipes and opening at different points into each passage for uniformly and evenly heating the retort, means for supplying gas to the burners, means for feeding coal at one

end of the retort and a gas chamber and take-off pipe at the other end of the retort.

2. The combination with a revoluble retort having in its walls a series of combustion flues and outlet ports therefrom, and a plurality of burners opening at different points into each flue, also having a central, coal feeding neck, of a fuel magazine connecting with said neck, a conveyer in the neck, a fixed collar on the neck and having an annular groove, the neck turning in the collar, a gas inlet pipe connecting with the collar at the groove, gas supply pipes or ducts in the retort head connecting with said groove and with the burners along the outside of the retort, and means for conducting off the evolved gas from the retort.

3. The combination with a revoluble retort having in its walls a series of combustion flues and outlet ports therefrom, and a plurality of burners provided with regulating valves and opening at different points into each flue, also having a central feeding neck, of a fuel magazine connecting with the neck, a conveyer in the neck, a fixed collar on the neck and having an annular groove, a gas inlet pipe connecting with the collar at the groove, gas supply pipes or ducts connecting with said groove and with the burners along the retort, a gas chamber at the discharge end of the retort and connecting therewith by an annular stuffing box, and a tight coke chamber connecting by a valved opening with the gas chamber.

In testimony whereof I affix my signature in presence of two witnesses.

WALTER THOMAS.
